K. VÖLLER.

GUN ADAPTED TO FIRE AT HIGH ELEVATIONS.

APPLICATION FILED MAY 4, 1910.

1,010,330.

Patented Nov. 28, 1911.

UNITED STATES PATENT OFFICE.

KARL VÖLLER, OF DUSSELDORF, GERMANY, ASSIGNOR TO RHEINISCHE METALL-
WAAREN- UND MASCHINENFABRIK, OF DUSSELDORF-DERENDORF, GERMANY.

GUN ADAPTED TO FIRE AT HIGH ELEVATIONS.

1,010,330.

Specification of Letters Patent.

Patented Nov. 28, 1911.

Application filed May 4, 1910. Serial No. 559,263.

To all whom it may concern:

Be it known that I, KARL VÖLLER, engineer, a subject of the German Emperor, residing at 17 Jülicherstrasse, Dusseldorf, 5 Germany, have invented certain new and useful Improvements in Guns Adapted to Fire at High Elevations; and I do hereby declare the following to be a full, clear, and exact description of the invention, such as 10 will enable others skilled in the art to which it appertains to make and use the same.

Guns designed to fire at high elevations cannot be loaded at these elevations, wherefore the gun barrel is brought into a particular 15 loading position when the gun is to be loaded. In order to render possible rapid loading a coupling inserted between the elevating mechanism and the gun barrel or the cradle is disconnected so that the barrel 20 can be swung into the loading position and back again into the firing position independently of the elevating mechanism.

When the gun has been loaded it may 25 happen that it is fired either by accident, or by oversight, while the barrel is still in the loading position. Should this occur the recoil brings the barrel back into the elevating position and not only is the shot fired uselessly but the blow which the gun barrel 30 deals the elevating mechanism is liable to break certain parts and to put the gun out of action. It is the object of the present invention to avoid such mishaps and for this 35 purpose when the coupling between the elevating mechanism and the gun barrel or cradle is disconnected a device automatically locks the trigger when the breech is closed and the trigger remains locked until the coupling has been again connected.

40 In the accompanying drawings the invention is illustrated in side elevation in Figure 1; in rear elevation in Fig. 2; and in plan in Fig. 3. Fig. 4 is a cross section.

The cradle carrier *c* which carries the 45 cradle *a* whereon the gun barrel *b* slides in recoiling, is mounted free to turn on trunnions *d* in the gun carriage. On the trunnion *d* the nave *e* of the toothed sector *f* is free to turn in the trunnion bearing. The sector 50 *f* is guided by a segmental rail *g* on the cradle carrier *c*; it engages a gear of an elevating mechanism which is not shown in the drawing and carries a sighting device of any suitable construction, also omitted 55 from the drawing. In a bearing *h*, fixed to

the cradle, slides a catch *i* which is retained by a spring *k* in the position shown in the drawing; in this position it engages a projection *m* of the toothed sector *f*. This projection is thus held against a surface of the bearing *h* so that the cradle *a* and the toothed sector *f* are coupled so as to move together. When, therefore, the toothed sector is moved, the cradle, the gun barrel and the sighting device move with it. The catch *i* has an eye *n* by which it is connected through link *o* with a lever *q* fixed to the shaft *p*; the latter can be moved by any suitable means in such a manner that the catch *i* is withdrawn from its engagement with the toothed sector *f* whereupon the cradle carrier *c* is disconnected from the sector. It is then possible to swing the cradle carrier *c* together with the cradle *a* and the gun barrel *b* independently of the toothed sector *f*, which, together with the elevating mechanism and the sighting device, remains in the position it has at the time.

On the cradle *a* is mounted to slide in a bearing *r* a piston *t* subject to the pressure of a spring *s*; this piston is maintained in the position shown in Fig. 1 by a lever *u* fulcrumed on the cradle *a*. The other end of this lever *u* rests upon a stop *v* fixed to the toothed sector *f*. When the coupling between the toothed sector *f* and the cradle carrier *c* or its guide rail *g* is disconnected and the cradle and gun barrel are turned on the trunnions, the lever *u* slides off the stop *v* and can turn about its fulcrum. In consequence the spring *s* presses upward the piston *t* until the latter comes against the top of the cylinder and thus turns the lever *u* through a small angle. The piston *t* carries an extension *w* which in the highest position of the piston presents itself in front of a lever *y*, fulcrumed in the breech block *x*, and prevents this lever from moving. The lever *y* is connected positively with the trigger of the gun in known manner so that the gun cannot be fired so long as the extension *w* locks the lever *y*, that is to say while the coupling is disconnected and the cradle carrier, together with the cradle and the gun barrel, is free to swing independently of the toothed sector. When, however, the gun barrel has been brought back into the firing position after loading and closing the breech, the free end of the lever *u* slides on

the inclined surface of the stop *v* and is thus raised so that the other end depresses the piston *t* with its extension *w* against the pressure of the spring *s* and thus liberates the lever *y* and the trigger.

Having now particularly described and ascertained the nature of my said invention and in what manner the same is to be performed, I declare that what I claim is:—

- 5 1. In combination with a gun having elevating mechanism, and a trigger-lock, means whereby the gun may be swung from firing to loading position independently of its elevating mechanism, means designed to be automatically actuated as the gun is so moved independently of its elevating mechanism to permit such trigger-lock to lock the trigger and keep it locked until the gun is returned to firing position.
- 10 2. In combination with a gun having elevating mechanism, and a trigger-lock, means whereby the gun may be swung from firing to loading position independently of its elevating mechanism, means designed to be automatically actuated as the gun is so moved independently of its elevating mechanism to permit such trigger-lock to lock the trigger and keep it locked until the gun is returned to firing position, and means for automatically releasing said former means when the gun is so returned to firing position.
- 15 3. In combination with a gun barrel adapted to fire at high elevations, a cradle for said barrel, and elevating mechanism for said barrel and cradle, means whereby the gun may be swung from firing to loading position independently of its elevating mechanism, a coupling between the elevating mechanism and the cradle, a trigger-lock, and means for permitting said trigger-lock to become effective when the barrel and cradle are, after the coupling is disconnected, moved into loading position independently of the elevating mechanism.
- 20 4. In combination with a gun barrel adapted to fire at high elevations, a cradle for said barrel, and elevating mechanism for said barrel and cradle, means whereby the gun may be swung from firing to loading position independently of its elevating mechanism, a coupling between the elevating mechanism and the cradle, a trigger-lock designed to automatically become effective when the coupling is disconnected and the barrel and cradle are moved into loading position independently of the elevating mechanism, and means for automatically retracting the trigger lock when the gun barrel and cradle are returned from loading position.
- 25 5. In combination with a gun barrel adapted to fire at high elevations, a cradle

for said barrel, and elevating mechanism for said barrel and cradle, between which latter and said elevating mechanism there is a relative movement, a coupling between the elevating mechanism and the cradle when the barrel and cradle are in firing position, a spring-impelled trigger lock for preventing the actuation of the trigger when the barrel and cradle are uncoupled from the elevating mechanism and are moved into loading position, and means for automatically retracting said trigger lock when the barrel and cradle are returned into firing position.

6. In combination with a gun barrel adapted to fire at high elevations, a cradle for said barrel, and elevating mechanism for said barrel and cradle, between which latter and said elevating mechanism there is a relative movement, a coupling between the elevating mechanism and the cradle, a pin for locking the trigger when the barrel and cradle are in loading position, and means for automatically moving said locking pin in opposite directions when the cradle and barrel are uncoupled from the elevating mechanism and are being moved relatively thereto.

7. In combination with a gun barrel adapted to fire at high elevations, a cradle for said barrel, and elevating mechanism for said barrel and cradle, between which latter and said elevating mechanism there is a relative movement, a spring-impelled trigger lock, a coupling between said elevating mechanism and cradle, a lever for moving said trigger lock in opposition to its spring when the barrel and cradle are uncoupled from the elevating mechanism, and are being moved into firing position, and fixed means for so acting on said lever.

8. In combination with a gun barrel adapted to fire at high elevations, a cradle for said barrel, and elevating mechanism for said barrel and cradle, between which latter and said elevating mechanism there is a relative movement, a spring-impelled trigger lock, a coupling between said elevating mechanism and cradle, a lever fulcrumed on said cradle for moving said trigger lock in opposition to its spring, and a stop carried by the elevating mechanism with which said lever is designed to engage to retract said trigger lock when the barrel and cradle are uncoupled from the elevating mechanism and are being moved to firing position.

In witness whereof I have hereunto set my hand in presence of two witnesses.

KARL VÖLLER.
